DESIGN FOR A PLATE OR SIMILAR ARTICLE

R. Guy Cowan, Syracuse, N. Y., assignor to Onondaga Pottery Company, Syracuse, N. Y., a corporation of New York

Application February 13, 1936, Serial No. 61,138

Term of patent 14 years

Be it known that I, R. Guy Cowan, a citizen of the United States, residing at Syracuse, in the county of Onondaga and State of New York, have invented a new, original, and ornamental Design for a Plate or Similar Article, of which the following is a specification, reference being had to the accompanying drawing, forming part thereof.

Figure 1 is a plan view; and Figure 2 is a cross-sectional view of a plate taken along line 2—2 of Figure 1 showing my design, it being understood that the ornamentation shown is continued throughout the rim of the plate.

The design consists in a plate or similar article having a narrow rim with the decoration shown incised in said narrow rim.

I claim:

The ornamental design for a plate or similar article substantially as shown and described.

In testimony whereof, I have hereunto signed my name, at Syracuse, in the county of Onondaga, and State of New York, this 11th day of February, 1936,

R. GUY COWAN.
